NECKTIE

James Fallar, Kitchener, Ontario, and Frank M. Richardson, Toronto, Ontario, Canada, assignors to Cluett, Peabody & Co., Inc., Troy, N. Y., a corporation of New York

Application September 11, 1934, Serial No. 743,500

10 Claims. (Cl. 2—150)

In tying neckties each edge of the front end of the tie should be folded forwardly within the knot so that when viewed from the front each edge is directed forwardly where it emerges from the lower end of the knot, the central portion being convex in cross-section and a valley appearing between the convex central portion and each outturned edge; or, depending upon the type of drape wanted, the edges may be folded backwardly with a concave cross-section in the middle and a convex cross-section on each side. Not only does this present the best appearance but it adds to the life of the tie by avoiding the crushing effect which results when the margins 10 of the tie are squeezed in with a multitude of small wrinkles instead of having a single fold near each edge.

According to the present invention the necktie is provided with fold lines extending longitudinally of the tie near the opposite edges respectively, whereby the tie tends to fold transversely as above described when knotted. The fold lines may extend the full length of the tie or only along and/or near the portion to be knotted, but in any event they must extend in the region of the knot. While the fold lines may be formed in many ways they are preferably formed in or by the lining, as for example by slitting the lining near the edges or making it stiffer and/or thicker along the margins than throughout the central portion.

For the purpose of illustration typical embodiments of the invention are shown in the accompanying drawing, in which

Fig. 1 is a front elevation of a knotted necktie, parts being broken away;

Fig. 2 is a section on the line 2—2 of Fig. 1;

Fig. 3 is a rear elevation of a portion of the lining of the embodiment illustrated in Fig. 2;

Fig. 4 is a section on line 4—4 of Fig. 3;

Figs. 5, 6 and 8 are views similar to Fig. 3 showing modifications;

Fig. 7 is a section of a necktie having a lining such as shown in Fig. 6; and

Fig. 9 is a front view showing the alternative type of drape above referred to.

In the particular embodiment shown in Figs. 1, 2 and 3 the lining L has two narrow strips secured along the margins in the region of the portion to be knotted. These strips may be formed of any suitable material such as a relatively stiff coarse material ordinarily used for tie linings, and the strips may be secured to the lining L in any suitable manner as, for example, by means of elastic stitching s. When the tie T is knotted

at k as shown in Fig. 1 the edges e are directed forwardly in and below the knot, the central portion c is convex in cross-section and between the convex central portion and each edge is a valley v. As shown in Fig. 2 the inner edges of the strips l are disposed in the region of the valleys v respectively, these edges constituting fold lines which give the tie a tendency to assume the shape shown in Figs. 1 and 2 when the tie is knotted in the usual way.

As shown in Fig. 5 the marginal strips l', corresponding to the strips l in Figs. 2, 3 and 4, may be formed integrally with the lining L' as lateral extensions and then folded inwardly over the body of the lining along the broken lines in Fig. 5.

In the modification shown in Figs. 6 and 7 the lining is formed of two pieces L'' and L² stitched together with elastic stitching along the three lines s', the front piece of lining L'' having two slits S extending therethrough to form the afore- said fold lines.

The embodiment shown in Fig. 8 is like that shown in Figs. 6 and 7 except that the second piece of lining material L² is omitted. Instead of or in addition to the slits the margins of the lining may be stiffened by impregnation with a suitable stiffener.

The tie may be draped with the edges directed forwardly as in Figs. 1 and 2 or rearwardly as in Fig. 9. In either case the aforesaid construction tends to cause the tie to fold near each edge instead of wrinkling as in usual constructions. With the edges folded backwardly as in Fig. 9 the front of the tie is concave at a and convex at b and b'.

It should be understood that the present disclosure is for the purpose of illustration only and that this invention includes all modifications and equivalents which fall within the scope of the appended claims.

We claim:

1. A necktie which, when knotted, automatically tends to fold transversely along longitudinal lines approximately midway between the middle and opposite edges respectively, comprising two thicknesses of lining material between each of said lines and the corresponding edge of the tie throughout the portion to be knotted, one thickness having edges extending along said lines to facilitate the aforesaid transverse folding.

2. A necktie which, when knotted, automatically tends to fold transversely along longitudinal lines approximately midway between the middle and opposite edges respectively, comprising two thicknesses of lining material through-

out the portion to be knotted, one thickness being slit along said lines only throughout said portion to provide edges which facilitate the aforesaid transverse folding.

5. 3. A necktie which, when knotted, automatically tends to fold transversely along longitudinal lines approximately midway between the middle and opposite edges respectively, comprising, in the knot portion of the tie, only one thickness of lining material between said lines and having only two thicknesses of lining material between each of said lines and the corresponding edge of the lining, thereby affording edges along said lines to facilitate the aforesaid trans-

15 verse folding.

4. A necktie which, when knotted, automatically tends to fold transversely along longitudinal lines approximately midway between the middle and opposite edges respectively, comprising 20 a fabric lining having slits extending along said lines throughout the portion to be knotted, the slits interrupting the transverse stiffness of the fabric sufficiently to facilitate said transverse folding but being sufficiently narrow not 25 substantially to effect the bulk of the knot.

5. A necktie which, when knotted, automatically tends to fold transversely along longitudinal lines approximately midway between the middle and opposite edges respectively, comprising 30 lining material having edges extending along said lines throughout the portion to be knotted and being stiffer between the lines and the lateral edges of the lining than between the lines.

6. A necktie which, when knotted, automatically tends to fold transversely along longitudinal lines approximately midway between the middle and opposite edges respectively, comprising 35 a lining which is stiffer between said lines and the edges throughout the portion to be knotted.

7. A necktie which, when knotted, automatically tends to fold transversely along longitudinal lines approximately midway between the middle and opposite edges respectively, comprising a lining which is stiffened by impregnation between 5 said lines and the edges throughout the portion to be knotted.

8. A necktie which, when knotted, automatically tends to fold transversely along longitudinal lines approximately midway between the middle 10 and opposite edges respectively, comprising two thicknesses of lining material between each of said lines and the corresponding edge of the lining throughout the portion to be knotted, one thickness having edges extending along said lines, 15 said edges being confined substantially to the portions to be knotted.

9. A necktie which, when knotted, automatically tends to fold transversely along longitudinal lines approximately midway between the middle 20 and opposite edges respectively, comprising a lining having two thicknesses throughout the portion to be knotted, one thickness being slit along said lines only throughout said portion to provide edges which are confined substantially to the 25 portion to be knotted.

10. A necktie which, when knotted, automatically tends to fold transversely along longitudinal lines approximately midway between the middle and opposite edges respectively, comprising 30 lining material in the central zone between said lines and in the marginal zones between said lines and said edges respectively, the lining in the marginal zones having, in the knot portion of the tie, edges at said lines approximately parallel with 35 the lateral edges of the tie.
